J. P. GIBSON.
COMBINED IRONING BOARD AND CLOTHES HANGER.
APPLICATION FILED APR. 19, 1920.

1,437,589.

Patented Dec. 5, 1922.

UNITED STATES PATENT OFFICE.

JOSEPH P. GIBSON, OF CHICAGO, ILLINOIS.

COMBINED IRONING BOARD AND CLOTHES HANGER.

Application filed April 19, 1920. Serial No. 374,954.

To all whom it may concern:

Be it known, that I, JOSEPH P. GIBSON, a citizen of the United States, residing at Chicago, in the county of Cook and State of Illinois, have invented certain new and useful Improvements in Combined Ironing Boards and Clothes Hangers, of which the following is a specification, reference being had to the accompanying drawings.

10 This invention relates to a combined ironing board and clothes hanger and particularly to an article of this character capable of being incorporated in a wardrobe trunk.

An object of the invention is to provide an 15 article of this character capable of being supported similar to the clothes hangers in a wardrobe trunk and used as a clothes hanger.

Another object is to provide an article of 20 this character capable of being supported at one end by a wardrobe trunk and at the other end by an auxiliary leg to permit the device to be used as an ironing board.

Another object is to provide an article of 25 this character whereby the usual broad end of the ironing board is constructed in the form of shoulders for use as a clothes hanger.

With these and other objects in view the invention consists in the improved construction and arrangement of parts to be herein- 30 after more particularly described, fully claimed and illustrated in the accompanying drawings, in which:

Figure 1 is a perspective view of a wardrobe trunk in open position with the invention applied and in its position as a clothes hanger.

Figure 2 is a side elevation of the wardrobe trunk with the device in the position when used as an ironing board.

40 Figure 3 is a fragmentary detail view of the upper portion of the clothes hanger and ironing board, and

Figure 4 is a top plan view with the upper portion of the compartment B removed.

45 Referring to the drawings, A designates a conventional form of wardrobe trunk including clothes compartment B and drawer section C. The compartment B is provided in its upper portion with the usual clothes hanger supporting rods D. A pair of supporting hooks 3 are provided, each hook including a supporting head 4 and having a

longitudinal slot. A screw 5 is extended through the slot and intended to hold the hooks in engagement with the trunk. These 55 hooks may be positioned in slots formed in either the compartment B or section C in any desired place so as to hold the device in a horizontal position. The screws 5 permit the hooks to be drawn outwardly when necessary and at the same time prevents them from being accidentally disengaged from the trunk.

A combined ironing board and clothes hanger is provided and consists of an ironing board 6 having the usual broad end 7 and narrow end 8. The broad end 7 includes extensions 9, which are formed into hooks 10 and also include eyes 11. The end portion 7 closely adjacent the extensions 9 is recessed 65 as at 12 to provide a supporting arm 13, the end portions formed by the recesses 12 inclines downwardly to form clothes supporting shoulders 15, the neck 16 preventing the arm 13 from coming in contact with the 70 clothes. In view of the fact that the sides of the ironing board taper toward the end 8 the shoulders 15 efficiently support the clothes in the well known manner without interference by the sides of the ironing 75 board.

80 A foldable leg 16 is hinged at its end 17 to the end portion 8 of the ironing board, the end portion 18 of the leg being provided with a spring clip 19 which is riveted to the leg 85 and may be swung to one side to permit the end 18 of the leg to engage the ground. When the leg 16 is not in use it is folded upon the ironing board 6, the spring clip 19 being disposed in engagement with the arm 90 13, the arm 13 having a recess 20 for the reception of the spring clip.

95 As illustrated in Figure 1 when the device is used as a clothes hanger the clothes are supported by the shoulders 15, the hook portions 10 being engaged with the usual supporting rods D of the clothes compartment. In addition to properly supporting the clothes, the ironing board holds the other clothes placed in the compartment so that 100 rough handling of the trunk will not cause bunching or creasing of the clothes.

When it is desired to use the device as an ironing board or as a table, the clothes are

removed from the shoulders 15 and the supporting hooks 3 extend outwardly from the drawer section *c*. The supporting arm is then supported by the hooks by passing the 5 latter through the eyes 11. The spring clip 19 is then disengaged from the arm 13 so as to permit the leg 16 to be swung downwardly into engagement with the floor. In this way the ironing board is held in a horizontal position 10 so that it may be used either for ironing or as a table. When the device is used as a clothes hanger, the novel form of catch being disposed in recess 20 does not interfere with the clothes that are supported by 15 the arm 13. If desired, various flat articles may be disposed between the leg 16 and the ironing board so that it may also be utilized when in its folded position. From the foregoing it will be readily seen that this ironing 20 board can be used without any additional support such as a table or chair. It does not contain any adjusting means or require that the leg be removed when the clothes are supported by the shoulders 15. Furthermore, 25 the supporting arm 13 occupies the same space and may be removed and applied similar to the usual clothes hanger used in wardrobe trunks and as the ironing board and clothes hanger, together with the supporting 30 arm, are made in one piece, the combined articles will last indefinitely as there are no parts to be loosened by rough handling of the trunk.

In addition to the above mentioned feature, a metal reinforcing member 21 is secured to the end portion 7 and extends over the extensions 9. It will be noted that the member 21 terminates adjacent the marginal edges of the extensions and is cut away at 35 its end portions as at 22 so as to reinforce the hooks 10. This reinforcing member braces the extensions 9 and prevents damage should the ironing board be accidentally dropped or be handled roughly.

I do not desire to limit myself to the construction of this combined clothes hanger and ironing board for use in wardrobe trunks, as the device can be readily supported in cupboards when used as a clothes 45 hanger and can also be supported by hooks carried by another supporting member such as a wall or table, to support the end 7 when the device is used as an ironing board.

What is claimed is:

1. The combination with a wardrobe trunk including clothes hanger supporting rods, of supporting hooks slidably mounted in one section of said trunk, an ironing board having an extension projecting from 50 the intermediate portion of one end, the end portion of said ironing board adjacent the extension forming clothes supporting shoulders, a supporting member formed integral with the extension and having its ends projecting beyond the sides of the ironing 55

board, the ends of said supporting member having supporting hooks and eyes, a leg hinged at one end to the other end of the ironing board, said hooks being engaged with the clothes hanger supporting rods 70 when the device is used as a clothes hanger, said first mentioned slideable hooks being disposed in the eyes and co-operating with the leg to support the ironing board in a horizontal position, and means for securing the 75 end of the leg to the supporting member.

2. The combination with a wardrobe trunk including clothes hanger supporting rods, of supporting hooks slidably mounted in one section of said trunk, an ironing 80 board having an extension projecting from the intermediate portion of one end, the end portion of said ironing board adjacent the extension forming clothes supporting shoulders, a supporting member formed integral 85 with the extension and having its ends projecting beyond the sides of the ironing board, the ends of said supporting member having supporting hooks and eyes, a leg hinged at one end to the other end of the 90 ironing board, said hooks being engaged with the clothes hanger supporting rods when the device is used as a clothes hanger, said first mentioned slideable hooks being disposed in the eyes and co-operating with 95 the leg to support the ironing board in a horizontal position, and a spring clip carried by the other end of the leg for engagement with the supporting member when the ironing board is used as a clothes hanger. 100

3. The combination with a wardrobe trunk including supporting means, of a combined ironing board and clothes hanger comprising a body member having one of its ends formed into clothes supporting shoulders, an extension extending from said end between the shoulders, oppositely extending arms projecting from the extension in spaced relation to said shoulders, said arms being arranged to support the body member 105 through the medium of said supporting means within the wardrobe trunk when used as a clothes hanger, said arms being arranged to support one end of the body member when used as an ironing board, a foldable supporting leg pivoted to the other end of the body member, said leg supporting the other end of the body member when used as an ironing board, and means carried by the other end of the supporting leg for engagement with the end of the extension when the leg is folded upon the body member. 110

4. The combination with a wardrobe trunk including a drawer section and a hanger section of an ironing board disposed within the hanger section, said ironing board having an extension at the intermediate portion of one end, said extension including oppositely extending arms, the end of each arm having a recess and an opening 115 120 125 130

adjacent the recess, said recess being adapted to engage supporting means within the hanger section, hooks slidably disposed in the drawer section and adapted to engage 5 the openings in said arms to support one end of the ironing board when removed from the hanger section, and means carried

by the other end of said board for supporting said end when the board is used for ironing.

10

In testimony whereof I hereunto affix my signature.

JOSEPH P. GIBSON.
